Inventor

J. Evans
By his Atty
H. Howdy

United States Patent Office.

JOHN EVANS, OF PHILADELPHIA, PENNSYLVANIA, ASSIGNOR TO HIMSELF
AND THOMAS H. SMITH, OF SAME PLACE.

Letters Patent No. 77,018, dated April 21, 1868.

IMPROVEMENT IN DOVE-TAIL MARKERS.

The Schedule referred to in these Letters Patent and making part of the same.

TO ALL WHOM IT MAY CONCERN:

Be it known that I, JOHN EVANS, of Philadelphia, Pennsylvania, have invented an Instrument wherewith to Mark Dove-Tails; and I do hereby declare the following to be a full, clear, and exact description of the same.

My invention consists of an instrument, fully described hereafter, for facilitating the marking of dove-tails on one board, and mortises for receiving the said dove-tails on another board, the instrument being such that when adjusted for marking the dove-tails, it is in a proper condition to determine the relative position of the mortises.

In order to enable others familiar with mechanism of this class to make and use my invention, I will now proceed to describe the mode of constructing and using the same, reference being had to the accompanying drawing, which forms a part of this specification, and in which—

Figure 1 is a perspective view of my instrument for marking dove-tails.

Figure 2, a front view, partly in section.

Figure 3, a plan view.

Figure 4, a transverse section on the line 1 2, fig. 2; and

Figures 5 and 6, views to illustrate the mode of using the instrument.

Similar letters refer to similar parts throughout the several views.

The frame, A, of the instrument consists of two plates, *a* and *a'*, situated at right angles to each other, and made in one piece.

In the plate *a* is an elongated opening, *b*, in which a cross-bar, *d*, is arranged to slide to and fro freely, the bar being attached to a rod, *e*, passing through a projection, *f*, provided with a set-screw, *h*, for securing the bar after adjustment.

The frame A is cut away near one end for the reception of a slide, B, composed of two plates, *i* and *i'*, arranged at right angles to each other, and made in one piece, the plate *i* being in the same plane with the plate *a* of the frame, and the plate *i'* in the same plane with the plate *a'* of the frame.

The lower edge of the plate *i* of the slide is grooved to receive guiding-pins, *j*, in the frame, as seen in fig. 2, and the plate *i'* of the slide is guided in a similar manner.

A lip, *k*, on the slide, overhangs the frame, and through a longitudinal slot in this lip passes a set-screw, *m*, into the frame, so that the slide can be secured after adjustment.

In using the instrument, the slide is adjusted to a proper position to mark a dove-tail of the desired size. It is then placed on the board, fig. 5, the plate *a* resting on the surface of the board, and the plate *a'* against the edge of the same. The first dove-tail, 2, is then marked on the top and edge of the board with a pencil or knife, guided by and following the edges, *x* and *x'*, of the frame, and the edges, *y* and *y'*, of the slide, fig. 1. After this, the instrument is moved in the direction of the arrow, fig. 5, to a point where it is desired to mark the next dove-tail, 3, after marking which, and before the instrument is removed, the cross-bar, *d*, is so adjusted that its front edge will coincide with the line *t* of the dove-tail 2, when the edge, *x*, of the instrument is coincident with the line *w* of the dove-tail 3, then the cross-bar is secured so as to serve as a guide in marking the remaining dove-tails, for when the instrument is moved along the edge of the board until the bar *d* coincides with the line *w* of the dove-tail 3, it is a certain indication that the instrument is in a proper position for making the third dove-tail, 4.

By the aid of the same instrument, with its stop unchanged, the mortises for the reception of these dove-tails are marked on the board, fig. 6, in a manner which will be readily understood, the bar, previously adjusted for the dove-tails, determining the proper distance apart of the mortises for receiving these dove-tails.

I claim as my invention, and desire to secure by Letters Patent—

1. The within-described instrument, consisting of the frame A, with its marking-edges *x* and *x'*, and the

slide B, with its marking-edges y and y' , the whole being constructed, arranged, and operating substantially as and for the purpose herein set forth.

2. The combination of the above with the adjustable plate d .

In testimony whereof, I have signed my name to this specification in the presence of two subscribing witnesses.

JOHN EVANS.

Witnesses:

JOHN WHITE,

C. B. PRICE.
